[57] **CLAIM**

The ornamental design for a knife rest or similar article, as shown and described.

DESCRIPTION

FIG. 1 is a top perspective view of a knife rest or similar article embodying my new design;
FIG. 2 is a front elevational view thereof, the rear view, not shown, is similar;
FIG. 3 is a bottom plan view thereof;
FIG. 4 is a left-side elevational view thereof;
FIG. 5 is a right-side elevational view thereof;
FIG. 6 is a front elevational view on an enlarged scale of a modification of my new design;
FIG. 7 is a rear elevational view thereof;
FIG. 8 is a cross-sectional view taken along the line 8—8 of FIG. 6; and
FIG. 9 is a cross-sectional view taken along the line 9—9 of FIG. 6.

FIG. 1

FIG. 2

FIG. 3

FIG. 4

FIG. 5

FIG. 8

FIG. 9
